attorney.

A. D. WILCOX, OF MANLIUS, NEW YORK.

Letters Patent No. 88,828, dated April 13, 1869.

IMPROVEMENT IN GATES.

The Schedule referred to in these Letters Patent and making part of the same.

To all whom it may concern:

Be it known that I, A. D. WILCOX, of Manlius, in the county of Onondaga, and State of New York, have invented a new and useful Improvement in Hanging Gates; and I do hereby declare that the following is a full, clear, and exact description thereof, which will enable those skilled in the art to make and use the same, reference being had to the accompanying drawings, forming part of this specification, in which—

Figure 1 is a front view of a gate having my improvement.

Figure 2 is a cross-section of the same, taken in the line *x x* in fig. 1.

Figures 3, 4, 5, and 6 are detail views.

Similar letters of reference indicate like parts in all the figures.

This invention relates to that class of gates which are opened partially by a sliding movement, and then swung fully open; and

The invention consists mainly in an improved construction of hinges, whereby both movements of the gate are obtained with the greatest facility, as herein-after explained.

In the accompanying drawings—

A is the gate, and

B, the posts.

The lower hinge of the gate is formed by a rim, C, (see sectional view fig. 5, and plan view fig. 6,) in which is supported a second rim, or ring, E, by means of a flange, c, on the lower edge of rim C.

The rim C is cast with a screw-spur, or bolt, C', by which it is secured firmly to the post B.

The rim E is placed loosely in the rim C, so as to be turned freely therein, and is provided with two notches, e e, fig. 6.

Within the rim E is suspended a flanged roller, F, the gudgeons of said roller having bearings in the said rim E. When the gate is pushed back, in making the first opening-movement, it rolls on the roller F, and then, when the gate is swung, the lower board engages

with the sides of notches e e, to turn the rim E within the outer rim C. A plain roller, without flanges, can be used in this hinge, as the notches e e will keep the roller in the proper position, relatively with the gate, without the use of flanges on said roller F, although these flanges are necessary in the upper hinge.

The upper hinge is formed by a rim, D, cast with a screw-spur, or bolt, D', as seen in fig. 3, for securing it to post B, and has an internal annular groove, d, for holding the gudgeons of the roller F, as shown in fig. 2, and, after the sliding movement has been made, in opening the gate, the upper board of the gate engages with the flanges f f of the roller, and causes its gudgeons to traverse the annular groove d, and thus the roller is made to follow the swinging-movement of the gate.

The gudgeons of the roller are inserted by first placing one gudgeon into the groove d, and then inserting the other through a notch, h, fig. 3.

To balance and sustain large gates, in the sliding movement, when nearly closed, a roller, H, is set in the ground between the posts B b, as shown in fig. 1.

To open the gate, it is first run back on the rollers until it is about balanced on its hinges, and it then receives a swinging-movement, to fully open the gate.

The hinges are cast complete, and require no fitting.

By these means, I produce hangings which are cheaply made, and which work in an efficient and satisfactory manner.

Having thus described my invention,

What I claim as new, and desire to secure by Letters Patent, is—

The hinges D d F f and C c E F, constructed as shown in fig. 2, and, in connection therewith, the balancing-roller H, as and for the purpose set forth.

The above specification of my invention, signed by me, this 22d day of December, 1868.

A. D. WILCOX.
